UNITED STATES PATENT OFFICE.

MATTHIAS SCHWEMBERGER AND ANTON GROESCHEL, OF CINCINNATI, OHIO,
ASSIGNORS OF ONE-THIRD TO L. H. BUHRMAN, OF SAME PLACE.

BUNG.

SPECIFICATION forming part of Letters Patent No. 399,086, dated March 5, 1889.

Application filed December 22, 1888. Serial No. 294,434. (No model.)

To all whom it may concern:

Be it known that we, MATTHIAS SCHWEMBERGER and ANTON GROESCHEL, citizens of the United States, residing at Cincinnati, 5 county of Hamilton, and State of Ohio, have jointly invented certain new and useful Improvements in Bungs, of which the following is a specification.

Our invention relates more specifically to 10 that class of bungs which are provided with vents; and it consists in a two-part body or frame adapted to carry a removable bung-piece of wood or other suitable material and having a valved vent-passage therethrough, 15 and in the details of construction hereinafter pointed out.

In the drawings, Figure 1 is a vertical section of our improved bung. Fig. 2 is an elevation of the same shown in position in a pack- 20 age.

A represents the wall of a cask or other pack- age; B, the ordinary bushing for a bung-hole; C, the body-piece of the bung-frame, having a flange, c, and a downwardly-extending screw- 25 threaded projection, c', adapted to take through an annular disk, D, of wood or other suitable material, which serves as the bearing-face of the bung.

E is a nut adapted to take over the screw- 30 threaded projection c' and serving to support the disk D and clamp it against the flange c, thereby re-enforcing the disk and tending to prevent breakage or warping. When the disk is worn or otherwise injured, it may be readily removed and a new one inserted, thus enabling the other and more expensive parts to 35 be used indefinitely.

The body-piece is provided with a suitable vent-passage, c'', of sufficient size at some convenient point to receive a downwardly-opening valve, F, which permits the ingress of air when the internal pressure is less than that of

the atmosphere, and prevents the escape of the gases within when the internal pressure is greater than that of the atmosphere. This 45 valve may be of rubber, and we have illustrated it as carried by a tubular projection, f, adapted to take into the vent-passage and press against the inner wall thereof, thereby holding the valve in position. An advantage 50 of this construction is that the valve may be readily removed and replaced by a new one when it becomes worn.

The body-piece is shown as provided at its upper extremity with a flanged head, c''', for 55 convenience in withdrawing the bung from its seat.

We claim—

1. A bung consisting of a flanged body-piece having a screw - threaded projection taking 60 through a disk, which forms the bearing-surface of the bung, a clamping-piece adjustable on such projection, a vent-passage through the bung, and a valve therein, substantially 65 as and for the purpose specified.

2. A bung consisting of a flanged body-piece having a screw - threaded projection taking 70 through a disk, which forms the bearing-surface of the bung, a clamping-piece adjustable on said projection, a vent-passage through the 75 bung, and a valve therein carried by a removable projection taking into said vent-passage, substantially as and for the purpose described.

3. A bung consisting of a body - piece, C, disk D, projection c', taking through said 75 disk, vent-passage c'', automatic downwardly-opening valve F, and removable projection f, substantially as and for the purposes specified.

MATTHIAS SCHWEMBERGER.
ANTON GROESCHEL.
